UNITED STATES PATENT OFFICE.

SMITH DAVENPORT PICKETT, OF ATLANTA, GEORGIA.

DESIGN FOR A BOTTLE.

Application filed October 6, 1923. Serial No. 7,416. Term of patent 14 years.

To all whom it may concern:

Be it known that I, SMITH D. PICKETT, a citizen of the United States, residing at Atlanta, in the county of Fulton and State of Georgia, have invented a new, original, and ornamental Design for Bottle, of which the following is a specification.

Referring to the drawing, forming part thereof.

The figure is a perspective view of a bottle, showing my new design.

I claim:

The ornamental design for a bottle, substantially as shown.

In testimony, that I claim the foregoing as my own, I have hereto affixed my signature.

SMITH DAVENPORT PICKETT.
